UNITED STATES PATENT OFFICE.

ERNEST H. PETTIT, OF NIAGARA FALLS, NEW YORK.

RAILROAD-TIE AND FASTENER.

1,188,313.

Specification of Letters Patent. Patented June 20, 1916.

Application filed October 22, 1915. Serial No. 57,359.

To all whom it may concern:

Be it known that I, ERNEST H. PETTIT, a citizen of the United States, residing at Niagara Falls, in the county of Niagara and 5 State of New York, have invented certain new and useful Improvements in Railroad-Ties and Fasteners; and I do hereby declare the following to be a full, clear, and exact description of the invention, such as will 10 enable others skilled in the art to which it appertains to make and use the same.

positioned inwardly of the plates 7, forming a seat 9, in which is seated a cushioning block 10. The cushioning block 10 may be constructed of any desired material, but it 60 is preferable to construct the same of a composition board, similar to the "beaver board", "compo board" or the like which is constructed of a form of paste board. The two cross bars 8 are connected by a longitudinally extending rib 11. The top section 65 of the plate 7 is provided with a slot 12 and depending

This invention relates to railway rail supporting ties, and fasteners, and the primary object of the invention is to provide a tie which is composed of a pair of sections, the uppermost of which sections carries the rail chairs and fastening means, and which is supported upon composite blocks carried by the ends of the other section of the tie, which blocks permit of a cushioning of the rails during the travel of rolling stock thereover.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like and corresponding parts throughout the several views, and in which:—

Figure 1 is a side elevation of the improved rail tie showing parts of the same in section. Fig. 2 is a fragmentary plan view of one end of the rail tie, showing a section of a railway rail supported thereby. Fig. 3 is a vertical cross section through one end of the railway tie. Fig. 4 is a perspective view of one end of the lower section of the tie.

40 of one end of the lower section.
Fig. 5 is a bottom perspective view of one
end of the cover or top plate or section of
the railway tie. Fig. 6 is a sectional view
on the line 6—6 of Fig. 2. Fig. 7 is a cross
45 section through a modified form of the rail
tie, and Fig. 8 is a longitudinal section of
the modified form of the rail tie.

Referring more particularly to the drawings, 1 designates a rail tie as an entirety, which is composed of an upper and lower section 2 and 3. The lower section 3, is substantially U-shaped, having a bottom plate 4 and upstanding sides 5 and 6. Cross ribs 7 and 8 extend across between the upstanding sides 5 and 6, adjacent to the outer ends

of the bottom sections 3. The plates 8 are positioned inwardly of the plates 7, forming a seat 9, in which is seated a cushioning block 10. The cushioning block 10 may be constructed of any desired material, but it is preferable to construct the same of a composition board, similar to the "beaver board", "compo board" or the like which is constructed of a form of paste board. The two cross bars 8 are connected by a longitudinally extending rib 11. The top section 2 includes a top plate 12 and depending sides 13 and 14, which overlap the upper edges of the upstanding sides 5 and 6 respectively, as is clearly shown in Fig. 3 of the drawings. The under surface of the top plate 12 rests upon the upper surface of the composite blocks 10.

The upper surface of the top side 12 of the top or upper section 2 has ribs 15 and 16 attached to its upper surface inwardly of each end which ribs are substantially triangularly shaped in cross section and have their straight sides facing toward each other. The rail clamps 17 and 18 have their outer edges abutting the straight sides of the ribs 15 and 16 respectively. The bolts 19 extend upwardly through the base or bottom 4, the composite block 10, the top side 12 and the rail clamps 17 and 18 and have nuts 20 mounted upon their upper ends for holding these members securely connected to each other. A novel form of nut lock is provided for preventing the nuts 20 from rotating upon the bolts 19. The nut lock includes metallic rods 21, which are bent to form substantially rectangularly shaped collars which engage the outer sides of the nuts 20. One end of the rod of which the nut locks are formed is bent downwardly from the rec- 95

tangular collar portion thereof and has its terminal split as is shown at 22, so that when the nut lock is driven over the nut the downwardly projecting portion 23 will extend through an opening 24 formed in the rail 100 clamps and the split end will engage the upper surface of the top plate or portion 12 which will spread the split portions of the downwardly extending portion 23 causing them to rest in recesses 25 formed in the 105 rail clamps and prevent the accidental removal of the nut locks 21 and also of the rotation of the nut upon the bolt. The rail clamps 17 and 18 have forwardly extending flanges 26 formed thereon which engage the 110

upper surfaces of the bases 27 of the ordinary T-rails 28. The depending sides 13 and 14 have lugs 29 formed thereon, which are provided for feeding in vertically extending recesses 30 formed in the upstanding sides 5 and 6 for properly positioning the upper and lower sections of the railway tie in being assembled and also for eliminating the liability of accidental longitudinal movement of one of the sections with respect to the other. A pair of depending ribs 33 are formed upon the inner surface of the top plate 12 and straddle the web 11.

In Figs. 7 and 8, a modified form of the improved rail tie is shown. The modified form illustrated in these figures comprises top and bottom sections 40 and 41. The bottom section 41 is a hollow rectangularly shaped member, which has a sheet 42 of cushioning material, mounted upon its upper surface, which cushioning material is the same as the material of which the blocks 10 are formed. The upper section 40, comprises a substantially hollow rectangular member having depending sides 43 and 44 formed upon and extending downwardly from its lower edges. The sides 43 and 44 extend over the longitudinal edges of the cushioning plate 42, and extend a short distance over the outer surfaces of the vertical sides of the lower section 41, as is clearly shown in Fig. 7 of the drawings. The upper section 40 has ribs 45 secured to its upper surface inwardly of its ends which ribs are substantially triangularly shaped in cross section having their vertical sides facing toward each other. The ribs 45 are rigidly secured to the upper surface of the upper section 40 and have the outer edges of the rail clamps 46 resting thereagainst. The rail clamps 46 are constructed identical to the rail clamps 17 and 18. Bolts 47 extend vertically through the section 41, the cushioning plate 42 and the top section 40 and the rail clamps 46. Nuts 48 are mounted upon the upper ends of the bolts and are locked against rotation by lock nuts 49 identical to the nut lock 21. The heads of the bolts 19 and 47 are countersunk in the under surfaces

of the plates 4 and the bottom of the section 50 41 respectively.

In reducing the invention to practice certain minor features of construction, combination and arrangement of parts may necessitate alterations to which the patentee is entitled provided such alterations are comprehended within the scope of what is claimed.

What is claimed is:—

1. In a railway tie structure, a railway tie composed of upper and lower sections, said lower section having upstanding sides, depending sides formed upon said upper section and overlapping the upper portions of the upstanding sides of said lower section, the upstanding sides of said lower section being provided with vertical recesses, lugs formed upon the inner surface of the depending sides of said upper section for feeding in said recesses for preventing accidental longitudinal movement of said sections with respect to each other, and means carried by said upper section for detachably attaching a railway rail thereto.

2. In a railway tie structure, a railway tie composed of upper and lower sections, said lower section having upstanding sides, depending sides formed upon said upper section and overlapping the upper portions of the upstanding sides of said lower section, the upstanding sides of said lower section being provided with vertical recesses, lugs formed upon the inner surface of the depending sides of said upper section for feeding in said recesses for preventing accidental longitudinal movement of said sections with respect to each other, and means carried by said upper section for detachably attaching a railway rail thereto, and composite cushioning blocks carried by said lower section, said upper section resting upon said composite cushioning blocks.

In testimony whereof I affix my signature in presence of two witnesses.

ERNEST H. PETTIT.
